H. T. SCOTT.
CARBURETOR ADJUSTING DEVICE.
FILED MAR. 30, 1922.

FIG. 1.

Inventor:
Harry T. Scott.

By *James T. Parker*,
his Attorney.

UNITED STATES PATENT OFFICE.

HARRY T. SCOTT, OF LOS ANGELES, CALIFORNIA.

CARBURETOR-ADJUSTING DEVICE.

Application filed March 30, 1922. Serial No. 548,222.

To all whom it may concern:

Be it known that I, HARRY T. Scott, a citizen of the United States, residing at Los Angeles, in the county of Los Angeles, 5 State of California, have invented new and useful Improvements in Carburetor-Adjusting Devices, of which the following is a detailed specification.

This invention has to do with a carburetor 10 adjusting device, and it is an object of the invention to provide a simple, compact, easily operated device of this character.

The device provided by the present invention is adapted to be used in a vehicle, 15 the carburetor of which has at least two adjustments, say for instance a liquid fuel adjustment and an air adjustment. The Ford motor car is a typical example of a motor vehicle in which the device of the present 20 invention can be advantageously installed. This particular make of vehicle is usually equipped with a carburetor having a fuel needle valve and an air valve, both of which require more or less regulation or adjustment. I am aware that devices have been proposed which attach to the adjustable parts of the carburetor and extend to the instrument board so that the adjustable parts can be independently adjusted from 25 the instrument board. Most of the devices of this character heretofore proposed have been characterized by having a single operating knob adapted to be operated in different manners to effect the adjustment of 30 the different parts. This invention provides a simple and compact means of adjusting a carburetor having two adjustments and accomplishing this without the use of clutches, slots, sliding key connections, etc., all of 35 which cause more or less lost motion. This invention also provides a particularly simple and neat means of operating two adjustments on a carburetor from one central point on the instrument board.

40 The object of this invention is to provide an improved simplified device of the general character just specified. Commercially it is important and desirable that a device of the character specified be simple and inexpensive of construction and further that it be simple and convenient of operation. The device provided by the present invention comprises two adjusting mechanisms which are entirely independent of each other oper- 45 atively, but which are combined in a simple, compact and neat manner into a single

structure. The operating knobs are arranged together at the instrument board so that they occupy a minimum amount of space and so that they can be easily and conveniently operated independently and without confusion.

The various objects and features of the invention will be best and more fully understood from the following detailed description of a typical preferred form of the invention throughout which reference is had to the accompanying drawings, in which:

Fig. 1 is a side elevation of a typical motor vehicle of the class to which the present invention is particularly applicable, certain of the parts of the vehicle being broken away for the purpose of illustrating the parts of the vehicle in connection with which the present invention is adapted to be arranged and for the purpose of showing the application of the device provided by the present invention; Fig. 2 is an enlarged view of certain of the parts shown in Fig. 1, being a view showing clearly the parts of the motor vehicle in connection with which the device of the present invention is arranged, and showing clearly the device of the present invention in connection with such parts; Fig. 3 is an enlarged detail sectional view taken as indicated by line 3-3 on Fig. 2; Fig. 4 is an enlarged detailed sectional view of certain of the parts shown in Fig. 2; Fig. 5 is a view taken as indicated by line 5-5 on Fig. 4; Fig. 6 is an enlarged detail sectional view taken as indicated by line 6-6 on Fig. 4; Fig. 7 is a sectional view of a portion of the carburetor of the vehicle showing the air throttle valve and the spring which normally holds it open; and Fig. 8 is a fragmentary sectional view showing another form of construction.

The present invention provides in combination a mechanism 10 for adjusting the needle valve 11 of the carburetor 12, and a mechanism 13 for adjusting the air throttle valve 14 of the carburetor 12. The preferred form of the present invention is adapted to be incorporated in a motor vehicle 15 of the general design and arrangement illustrated in Fig. 1, that is a motor vehicle having a carburetor 12 with two parts adapted to be adjusted, a dash-board 16, an instrument board 17, arranged somewhat rearward of the dash-board 16, etc. The particular carburetor 12 which I have illustrated in the

drawings is of typical design and construction and is connected with the intake manifold 18 of the vehicle engine 19 in the usual manner.

- 5 The adjusting mechanism 10 comprises a rod 20 which is connected at 21 with the valve stem 11 of the carburetor 12 and extends upwardly and rearwardly to and through the dash-board 16, a rod 22 located 10 between the dash-board 16 and instrument board 17 and connected with the rod 20 by a suitable universal joint 23, a tube 24 which connects to the rod 22 and extends through the instrument-board 17, and an operating 15 knob 25 secured on the tube 24 at the front of the instrument board 17. The rod 20 is a part usually provided on vehicles of the type under consideration and therefore is looped at its upper end to form a handle. 20 The universal joint 23 which I provide has a yoke part 27 adapted to receive and attach to the looped handle part of the rod 20. The rod 22 is preferably an ordinary round rod and the universal joint 23 is provided 25 with a socket part 28 which receives and holds one end of it. The rod 22 extends a portion of the way from the universal joint 23 to the instrument board 17. The tube 24 is secured to the rod 22 and extends there- 30 from through the instrument board 17. It will be obvious that the tube 24 might be integral with the rod 22 and might be formed by drilling into the end of the rod. The operating knob 25 is secured on the 35 tube 24 at the front of the instrument board 17, for instance it may be cast on the end of the rod 24, and is preferably T-shaped, as I have illustrated in the drawings. In accordance with the preferred form of construction a helical spring 30 is carried on the tube 24 between a suitable part of the instrument board 17 and a collar 31 which bears against a snap ring 32 on the tube 24. The snap ring 32 extends substantially 40 half way around the tube 24 and has its ends 33 turned inwardly to extend into holes provided for that purpose in the tube 24, as clearly illustrated in Figs. 4 and 6 of the drawings. The spring 30 operates to 45 keep the hub 34 of the operating knob 25 tight against the instrument board 17 so that it does not rattle and so that the mechanism just described is not rotated by vibration or jarring of the machine. 50 To operate the mechanism 10 the operator 55 grips the operating knob 25 and rotates it, thus causing rotation of the tube 24 and rod 22 which, through the universal joint 23, causes rotation of the rod 20 and therefore rotation of the needle valve 11 of the carburetor 12. It is preferred in practice 60 to provide limiting means in connection with the mechanism just described in order to limit the amount the valve 11 can be 65 adjusted and to enable the operator to con-

veniently determine about what position the valve is in. For this purpose I prefer to secure a stop member 37 to a stationary part of the carburetor 12 and to secure a stop member 38 to the valve 11 so that it will cooperate with the stop member 37, as illustrated in Fig. 2. The stop member 38 is preferably designed and proportioned so that it will cooperate with a stationary part of the carburetor as well as with the stop member 37 and thus operate to limit the movement of the valve 11 in both directions. 70

The adjusting mechanism 13 comprises a rod 40 slidably carried in the tube 24 so that it has one end extending through a suitable opening 41 in the operating knob 25 and projecting from the operating knob 25, a flexible member 42 which is attached to the other end of the rod 40 and extends 80 through an opening 43 in the tube 24 and connects with the valve 14 of the carburetor 12, say for instance through a bell crank 44 and connecting rod 45 in the manner illustrated in Fig. 2 and an operating knob 61 secured on the rod 40 at the front of the instrument board. The valve 14 is provided with an operating arm 46 and also with a spring 47 which normally holds the valve open. The bell crank 44, as I have 85 illustrated in Fig. 2 of the drawings, is pivotally carried by bracket 50. The flexible member 42 attaches to the arm 51 of the bell crank 44, while the rod 45 attaches to the arm 53 of the bell crank 44. The flexible member 42 may in practice be a piece of wire, cable, or the like, and may be attached to the rod 42 and arm 51 in any convenient manner. In the drawings I have shown the member 42 with one end folded over and secured in an opening 55 in the end of the rod 40 by solder 56 or the like, and have shown the other end of the member 42 arranged through an opening 57 in a bolt 58 which is pivotally carried by the arm 51. 90 The end of the member 42 is secured in the opening 57 by a nut 59 which is screw threaded on the bolt 58 to press the washer 60 into engagement with the member 42 in the manner clearly illustrated in Fig. 3. On the end of the rod 40, which projects from the operating knob 25 I secure the operating knob 61. The operating knob 61 is preferably a round knob, such as I have 95 illustrated in the drawings so that it will be distinctly different from the operating knob 25. 100

To operate the mechanism 13 the operator 105 grips the knob 61 and pulls it outwardly, thus causing the rod to be moved outwardly in the tube 24 and therefore causing 110 the flexible member 42 to move and operate the bell crank 44 which in turn, through the rod 45, operates the valve 14. If the mechanism 13 is released in its actuated position it 115 is immediately returned to its unactuated 120 position. 125

position, as illustrated in the drawings, by the spring 47 in connection with the valve 14.

In Fig. 8 I show the adjusting mechanism 13 connected with the valve 14 in another manner from that just described. The flexible member 42 in place of connecting with a bell crank, which in turn is connected with the valve 14 through a rod 45, extends over a roller 70 mounted on the dash board 16 and extends therefrom directly to the operating arm 46 of the valve 14. This particular manner of connecting the mechanism 13 with the valve 14 is particularly desirable and effective.

From the foregoing description it will be readily understood how the present invention provides two adjusting mechanisms 10 which are entirely independent operatively but which are combined into a single structure so that they occupy a minimum amount of space, are simple, neat, and still effective. Further, it will be noted that the present invention in providing two distinct operating knobs eliminates to a great extent the possibility of the operator becoming confused and making the wrong adjustment as often occurs when both adjustments are made through a single operating knob. The fact that the operating knobs 25 and 61 are different in design and formation is particularly noteworthy and desirable in that it minimizes the possibility of confusion and enables the operator to conveniently grip either of the knobs without in any way interfering with or operating the other.

Having described only a typical preferred embodiment of my invention I do not wish to limit myself to the particular details hereinabove set forth but wish to reserve to myself any changes or variations that may appear to those skilled in the art or fall within the scope of the following claims.

Having described a preferred form of my invention, I claim:

1. In combination with a vehicle including an instrument board and a carburetor with two adjustable parts, an adjusting mechanism for one of the parts including a tube extending through the instrument board and having an opening in it at one side of the instrument board, an operating knob attached to the tube at the other side of the instrument board, and connecting means between the tube and said part whereby rotation of the tube causes adjustment of said part, and an adjusting mechanism for the other of said parts including a rod slidably carried in said tube, an operating knob in connection with the rod at the other operating knob, and means connecting the rod and said other part through the opening in the tube whereby longitudinal movement of the rod causes adjustment of said other part.

2. In combination with a vehicle includ-

ing an instrument board and a carburetor 65 with two adjustable parts, an adjusting mechanism for one of the parts including a tube extending through the instrument board and having an opening in it at one side of the instrument board, an operating knob attached to the tube at the other side of the instrument board, yielding means for normally keeping said operating knob in pressure engagement with the instrument board, and connecting means between the tube and 70 said part whereby rotation of the tube causes adjustment of said part, and an adjusting mechanism for the other of said parts including a rod slidably carried in said tube, an operating knob in connection with the 75 rod at the other operating knob, and means connecting the rod and said other part through the opening in the tube whereby longitudinal movement of the rod causes adjustment of said other part.

3. In combination with a vehicle including an instrument board and a carburetor with two adjustable parts, an adjusting mechanism for one of the parts including a tube extending through the instrument 90 board, and having an opening in it at one side of the instrument board, an operating knob attached to the tube at the other side of the instrument board, and connecting means between the tube and 95 said part whereby rotation of the tube causes adjustment of said part, said connecting means including a rod attached to the tube, a rod attached to said part, and a flexible connection between the rods, and an adjusting 100 mechanism for the other of said parts including a rod slidably carried in said tube, an operating knob in connection with the rod at the other operating knob, and means connecting the rod and said other part 105 through the opening in the tube whereby longitudinal movement of the rod causes adjustment of said other part.

4. In combination with a vehicle including an instrument board and a carburetor 110 with two adjustable parts, an adjusting mechanism for one of the parts including a tube extending through the instrument board and having an opening in it at one side of the instrument board, an operating 115 knob attached to the tube at the other side of the instrument board, and connecting means between the tube and said part whereby rotation of the tube causes adjustment of said part, and an adjusting mechanism for 120 the other of said parts including a rod slidably carried in said tube, an operating knob in connection with the rod at the other operating knob, and means connecting the rod and said other part through the opening in 125 the tube whereby longitudinal movement of the rod causes adjustment of said other part, said last mentioned means including a flex-

ible member connected with the rod within the tube, arranged through the opening in the tube and connected with said other part.

5. In combination with a vehicle including an instrument board and a carburetor with two adjustable parts, an adjusting mechanism for one of the parts including a tube extending through the instrument board and having an opening in it at one side of the instrument board, an operating knob attached to the tube at the other side of the instrument board, yielding means for normally keeping said operating knob in pressure engagement with the instrument board, said yielding means including a part secured to the tube and a spring arranged between said part and the instrument board, and connecting means between the tube and said part whereby rotation of the tube causes adjustment of said part, and an adjusting mechanism for the other of said parts including a rod slidably carried in said tube, an operating knob in connection with the rod at the other operating knob, and means connecting the rod and said other part through the opening in the tube whereby longitudinal movement of the rod causes adjustment of said other part.

6. In combination with a vehicle including an instrument board and a carburetor with two adjustable parts, an adjusting mechanism for one of the parts including a tube extending through the instrument board and having an opening in it at one side of the instrument board, an operating knob attached to the tube at the other side of the instrument board, and connecting means between the tube and said part whereby rotation of the tube causes adjustment of said part, and an adjusting mechanism for the other of said parts including a rod slidably carried in said tube, an operating knob in connection with the rod at the other operating knob, and means connecting the rod and said other part through the opening in the tube whereby longitudinal movement of the rod causes adjustment of said other part, one of said operating knobs being round and the other T-shaped.

50 7. In combination with a vehicle including an instrument board and a carburetor with two adjustable parts, an adjusting mechanism for one of the parts including a tube extending through the instrument board and having an opening in it at one side of the instrument board, an operating

knob attached to the tube at the other side of the instrument board, and connecting means between the tube and said part whereby rotation of the tube causes adjustment of 60 said part, said connecting means including a rod attached to the tube, a rod attached to said part, and a flexible connection between the rods, and an adjusting mechanism for the other of said parts including a rod slidably carried in said tube, an operating knob in connection with the rod at the other operating knob, and means connecting the rod and said other part through the opening in the tube whereby longitudinal movement of 70 the rod causes adjustment of said other part, said last mentioned means including a flexible member connected with the rod within the tube, arranged through the opening in the tube and connected with said other part. 75

8. In combination with a vehicle including, a dash board, an instrument board and a carburetor with two adjustable parts, means for limiting the adjustment of one of the parts including a member attached to a 80 stationary part of the carburetor and a member attached to said part, an adjusting mechanism for said part including a tube extending through the instrument board and having an opening in it at the inner 85 side of the instrument board, an operating knob attached to the tube at the outer side of the instrument board, a rod attached to the tube, a rod attached to said part and extending therefrom through the dash board, 90 a member secured to the tube, and a spring arranged between the member and instrument board to hold the operating knob in pressure engagement with the instrument board, and an adjusting mechanism for the 95 other of said parts including a rod slidably carried in said tube, an operating knob in connection with the rod at the other operating knob, and means connecting the rod and said other part through the opening in the 100 tube whereby longitudinal movement of the rod causes adjustment of said other part, said last mentioned means including a flexible member connected with the rod within the tube, arranged through the opening in the 105 tube and connected with said other part, one of said operating knobs being round and the other T-shaped.

In witness that I claim the foregoing I have hereunto subscribed my name this 15 110 day of March 1922.

HARRY T. SCOTT.
